US0D1113800S

(12) **United States Design Patent** (10) Patent No.: **US D1,113,800 S**
(45) Date of Patent: ** Feb. 17, 2026

(54) **SPEAKER**

(71) Applicant: **Lianming Wang**, Yueyang (CN)

(72) Inventor: **Lianming Wang**, Yueyang (CN)

(**) Term: **15 Years**

(21) Appl. No.: **29/997,737**

(22) Filed: **Apr. 9, 2025**

(51) LOC (15) Cl. **14-01**

(52) U.S. Cl.

USPC **D14/204**

(58) **Field of Classification Search**

USPC ... D14/204, 205, 207, 209.1, 214, 215, 217,
